UNITED STATES PATENT OFFICE

ALBERT RODRIAN, OF POTSDAM, GERMANY

TYPE HEAD FOR TYPEWRITERS AND THE LIKE

Application filed December 16, 1927, Serial No. 240,531, and in Germany March 24, 1927.

My invention relates to improvements in type heads adapted to be mounted on type levers such as are used in typewriters. The benefit of the invention is found in the operation in which the type head and lever to be connected are placed on a gauging apparatus, the correct relative position of the head and lever being insured by means of a mark such as a nose corresponding to a corresponding indentation provided on the gauging apparatus. In the method now in use the gauge mark is provided between pairs of types provided on the type head, the said mark being either in the form of a nose projecting 5 from the head or of an indentation. I have found that when providing a nose on the type head the said nose will produce an impression on the paper when using the type lever in the typewriting machine, because the 10 said nose is necessarily close to the types. When constructing the said mark in the form of an indentation it is difficult to manufacture the die from which the types are made, for the reason that the portion of the die forming 15 the indentation projects from the bottom of the die while the portions forming the letters are sunk in the said bottom. Thus when cutting the die the steel block must have a thickness such that a thickness corresponding 20 to the height of the projecting portion can be removed, so that the cost of manufacturing the die is comparatively high. Furthermore, in the cutting of the die, it is impossible to form with sufficient accuracy 25 of spacing both a sunk letter and a projecting mark upon the face of the die. The object of the improvements is to provide a method in which the said objections are obviated, and with this object in view my invention consists 30 in providing the type head at one end only with a mark in the form of a projecting nose, the said mark being spaced from the type head so far that it does not spoil the paper 35 when printing. In the preferred embodiment my invention consists in providing the mark on a portion of the type head which can be readily removed from the body thereof, the said portion being preferably reduced in 40 thickness as compared to the body of the type

head or separated therefrom by an indentation.

In order that my invention be more clearly understood an apparatus suitable for putting my improved method into effect has been 55 shown in the accompanying drawing, in which

Fig. 1, is a sectional elevation showing the gauging apparatus with a type lever and type head placed thereon,

Fig. 2, is a top plan view of Fig. 1,

Fig. 3, is a detail view on an enlarged scale and partly in section and showing the type head and a part of the gauging apparatus, and

Fig. 4, is a sectional elevation taken on the line 4—4 of Fig. 3.

In the example shown in the drawing the gauge apparatus comprises a gauge block 1 in the form of a segment the dimensions of 70 which correspond to the segment of the typewriting machine on which the type levers are mounted, and a gauge block 6 adapted to receive the type heads 7 in the proper position relatively to the segmental gauge block 1. 75 The blocks 1 and 6 are fixed to a base plate 5 by means of screws 18 and 19, the relative positions of the said parts being such that when fixing the type head 7 to the type lever 3 the types are in the correct position relatively to the segment of the typewriting machine and the printing point thereof. The levers 3 are mounted on the block 1 in the proper position by means of a pivot bolt 4. Further, the block 1 is formed with an abutment 9 corresponding to a nose 10 formed on the lever 3, the object of the said abutment and nose being to hold the outer end of the type lever the proper distance away from the top face of the block 6. Further, to the block 90 1 an arm 2 is fixed which is turned upwardly at its outer end, the said upwardly projecting end being formed with a notch corresponding to a heel 11, formed on the outer end of the lever 3. Thus the outer ends of 95 the levers placed on the block 1 are held in the proper position relatively to the block 6 by the said arm.

As shown, the type head is formed with two types 15 and 16, and in addition it is 100

formed at its outer end with a heel 8 formed at its nether face with a nose 13. The gauge block 6 is formed at its top face with a recess 14 adapted to receive the types 15 and 16, and the inner part of the bottom of the said recess 14 is elevated so far that the type head placed on the block in the correct position bears with the face of the inner type 16 on the said raised part of the bottom. Further, the block 6 is formed with an indentation 23 corresponding to the nose 13. Thus, when placing the type head 7 on the block 6, the head is supported with its type 16 on the elevated portion 12 of the bottom of the recess 14 and with its nose 13 in the indentation of the block 6, and the distance between the indentation 23 and the pivot bolt 4 is such that the type head 7 placed on the block 6 is the proper distance away from the pivot bolt 4. It will be understood that in all the type heads to be adjusted by means of the gauging apparatus the distance between the nose 13 and the types 15 and 16 is exactly alike.

For fixing a type head 7 to the type lever 3 the said lever is placed on the block 1 so that the pivot bolt 4 passes through the bore of the lever 3 corresponding thereto, and the nose 10 bears on the abutment 9. The end of the type lever engages with the heel 11 in the notch of the arm 2 corresponding thereto. Thus the type lever 3 is exactly in the correct position. The type head 7 corresponding to the key lever 3 is placed on the block 6 with the nose 13 fitting in the indentation 23 and the type 16 bearing on the portion 12 of the bottom of the recess. Now the head 7 is soldered or otherwise fixed to the key lever 3.

The type head 7 is shaped in a die or matrix and this die or matrix is shaped by cutting with a fraising tool. If the positioning means employed for setting the type head 7 upon the gauge block 6 were in the form of a recess upon the type head and a nose upon the gauge block, positioning could not be effected with sufficient accuracy. The recesses in the die or matrix in which the types 15 and 16 are themselves formed are cut by means of the tool alluded to, and this tool is adjustable by screw feed; and if, in addition to the recesses for the types, a further recess be formed within which to shape a nose as one element of the positioning means, such recess may be cut by the same tool under the same screw feed, and, accordingly, accuracy of spacing as between recess for type and recess for nose is possible. But if, instead of a nose, the type head 7 were to be provided with a recess, as its element of the positioning means, the die or matrix would have to be formed with a corresponding projection, and such projection upon the face of the die or matrix would have to be formed by a tool adjusted in a different manner, and the positioning of the projection rela-

tively to the recesses for the types would have to be determined by the eye, and determination by eye could not afford a sufficiently accurate result. The element of the positioning means which the type head 7 carries must, therefore, be a projection, as the type also which the type head carries are projections. Otherwise, accuracy of spacing as between the type themselves and the positioning means is impossible of accomplishment. A difficulty, however, remains; as already stated, it is objectionable that the type head carry as its element of the positioning means a projection, for the projection being present is liable to make unsightly marking upon the paper when the type head is in service. My invention then involves further the formation of this projecting element or nose upon a deciduous extension of the type head, and, after the positioning means have served their purpose, this extension is cut away. Thus the desired accuracy is achieved without prejudice to the utility of the finished article.

As appears from Fig. 2, the segment 1 is formed with a series of slots 22 each adapted to receive a key lever.

After the type head has been fixed to the key 3 the heel 8 is removed therefrom by means of a pair of tongues, by grinding, or by other methods.

In the example shown in the figures a gauging apparatus independent of the typewriting machine is provided for fixing the type heads to the type levers. But I wish it to be understood that I do not limit myself to this feature, and that in some cases the segment 1 is taken from the typewriting machine to be provided with the type levers, so that a separate segmental block 1 may be dispensed with. Further, the operation of adjusting the type heads and fixing the same to the type levers may be performed on the typewriting machine itself, in which case a gauge block such as 6 is temporarily fixed to the typewriting machine in the proper position relatively to the segment having the type levers pivotally mounted thereon.

I claim:

1. A type-head, adapted for assembly in properly gauged space relationship with a type-lever, said type-head consisting of a body provided with a plurality of projecting types and provided further with the projecting element of a projection-and-recess alignment device, such member being arranged beyond the area included by and between said types and being accurately spaced with respect to said types.

2. A type-head, adapted for assembly in properly gauged space relationship with a type-lever, said type-head consisting of a body provided with projecting type and provided further with a removable lateral extension, such lateral extension bearing a pro-

jecting nose accurately spaced with respect to said type and adapted to engage a corresponding recess in a carrier.

3. In apparatus for adjusting type-heads on type-levers, a carrier equipped at one end with positioning means adapted to be engaged by the type-lever and at the other end with a seat upon which the type-head may be adjusted to position; the carrier being further provided adjacent such seat, and beyond such seat and on the side thereof opposite the said type-lever positioning means, with a type-head positioning device, such type-head positioning device being adapted to cooperate with a type-head equipped with a complementary part and by such cooperation to effect accurate placement of the type-head on such seat.
